(57) **CLAIM**

The ornamental design for a gun sight, as shown and described.

DESCRIPTION

FIG. 1 is a rear perspective view of a gun sight in accordance with this invention.

FIG. 2 is a left elevational side view of the gun sight of FIG. 1.

FIG. 3 is a right elevational side view of the gun sight of FIG. 1.

FIG. 4 is a front view of the gun sight of FIG. 1.

FIG. 5 is a rear view of the gun sight of FIG. 1.

FIG. 6 is a top view of the gun sight of FIG. 1; and,

FIG. 7 is a bottom view of the gun sight of FIG. 1.

The broken line representations of a rear portion of a handgun in FIGS. 1 and 2 are for the purpose of illustration only and form no part of the claimed design.
